UNITED STATES PATENT OFFICE.

JOHN MACDONALD AND THOMAS MACDONALD, OF GLASGOW, SCOTLAND.

PORTABLE HEATER FOR HEATING RIVETS, &c.

SPECIFICATION forming part of Letters Patent No. 740,670, dated October 6, 1903.

Application filed May 6, 1903. Serial No. 155,819. (No model.)

To all whom it may concern:

Be it known that we, JOHN MACDONALD and THOMAS MACDONALD, engineers, subjects of the King of Great Britain, residing at 9 York street, Glasgow, Scotland, have invented certain new and useful Improvements in Portable Heaters or Forges for Heating Rivets and for Such Like Purposes, of which the following is a specification.

10 This invention relates to portable heaters or forges for heating rivets and for such like purposes.

At present portable rivet-heaters are usually provided with an air-blast produced by the action of a bellows or the operation of a fan or blower. It has been proposed to do away with the bellows and fan and introduce a jet of compressed air direct to the twyer, the compressed air being drawn from any suitable or convenient air-compressing apparatus. It may be pointed out that while the use of a compressed-air jet directed into the twyer as aforesaid obviates the necessity for employing a boy to operate a fan or bellows, and thus far results in economy, yet great waste occurs through the large amount of compressed air which has to be used in order to produce an efficient blast. The result is that the economy in labor is more than counterbalanced by the waste of compressed air.

Under our invention we propose to use a fan or air-propeller and operate said fan or propeller by means of a small jet of compressed air, with the result that while the services of a boy for operating the fan are dispensed with only a comparatively small quantity of compressed air is used.

In order that our invention may be properly understood, we have hereunto appended two sheets of drawings, whereon is shown, by way of example, a portable rivet-heater, such as used in ship-yards, said heater being constructed with our improvements.

45 Figure 1 is a side elevation of the rivet-heater. Fig. 2 is a section through the fan-casing of the rivet-heater. Fig. 3 shows the compressed-air nozzle full size. Fig. 4 is a longitudinal section of same.

50 The rivet-hearth *a* is made of sheet metal and circular, as usual. *a'* represents the supporting-legs. The

sides *b* are preferably carried up higher than the front part *c*.

d represents the usual twyer in dotted lines. 55

e is the air-blast pipe leading to the twyer.

f is a rotary fan or air-propeller arranged below the hearth and adapted to deliver the air-current into the pipe *e*.

g is the casing of the fan, and *h* the air-inlet opening in the casing.

The fan may be of any well-known and suitable construction and with radial or other blades or vanes. The fan shown on the drawings has eight radial vanes. 65

At the top of the casing is a pop *i*, made with an inclined and tapped hole, into which is screwed a nozzle *j*, said nozzle having a passage-way *j'* in it, forming at one end a seat for the air-admission valve. The air-admission valve preferably consists of a needle or spindle *o*, working in a casing *p*, which may be screwed to the nozzle *j* and which is provided with a branch *p'*, connected with the compressed-air-supply pipe *k*. The spindle 70 *o*, one end of which terminates in the valve *o'*, is screwed at *q* and has fitted to it a disk or wheel *r*, (provided with an external flange or rim *r'*), by means of which it can be turned and the distance of the valve *o'* from the seat 80 varied, thereby regulating the quantity of air admitted to the fan *f*. The spindle *o* is made larger at the screwed end *q*, so that when desired it can be readily withdrawn from the casing *p* for cleansing or other purposes. 85

The method of fitting the several parts together will be easily understood without further explanation, as the drawings show everything quite clearly.

When the compressed air is turned on by 90 opening the valve *o'*, a fine jet of air issues with considerable force from the nozzle *j* and impinges on the vanes of the fan, propelling it around very rapidly. The revolution of the fan draws air in through the opening *h* 95 and forces it up the pipe *e* and through the twyer.

The fan can be started and stopped when desired by manipulating the air-cock *n* or valve *o*. If desired, the cock *n* may be dispensed with.

The rivet-heater is preferably made without side handles.

Having now fully described our invention,

what we claim, and desire to secure by Letters Patent, is—

1. In a portable heater or forge for heating rivets and for such like purposes the combination with the twyer of a fan or air-propeller for delivering an air-blast to the twyer and means whereby the fan or propeller can be rotated by a jet of compressed air which is caused to impinge on the blades of the fan.
2. In a portable heater or forge the combination with the hearth and the twyer of a rotary fan for delivering an air-blast to the twyer, an air-nozzle arranged in the casing of the fan and adapted to deliver a jet of compressed air against the blades of the fan, and means for supplying compressed air to the nozzle.
3. In a portable heater or forge the combination with the hearth and the twyer of a rotary fan for delivering an air-blast to the twyer, an air-nozzle arranged in the casing of the fan and adapted to deliver a jet of compressed air against the blades of the fan, means for controlling the passage of air through the nozzle, and means for supplying compressed air to the nozzle.
4. In a portable heater or forge the combination with the hearth and the twyer of a rotary fan for delivering an air-blast to the twyer, a valve-casing provided with a nozzle arranged in the casing of the fan, a needle-valve arranged within the valve-casing, means for manipulating the valve, and means for supplying compressed air to the valve.
5. In combination, the hearth, the twyer,

a rotary fan for delivering an air-blast to the twyer, a casing surrounding the fan, a nozzle screwed into the casing, a valve-casing screwed onto the nozzle, a needle-valve arranged within the valve-casing and adapted to close the orifice of the nozzle, means for manipulating the valve, and means for supplying compressed air to the valve-casing.

6. In combination, the hearth, the twyer, a fan arranged below the hearth and adapted to rotate within a casing, a blast-pipe leading from the casing of the fan to the twyer, an air-outlet at the side of the fan-casing, a pop on the casing, a needle-valve provided with a screwed nozzle inserted in the pop, means for manipulating the needle-valve and means for supplying compressed air to the valve, substantially as hereinbefore described.

7. In a portable heater or forge, the combination with the hearth and the twyer, of a rotary fan for delivering an air-blast to the twyer, a valve-casing provided with a nozzle arranged in the casing of the fan, a valve arranged within the valve-casing, means for manipulating the valve, and means for supplying compressed air to the valve.

Signed at Glasgow, Scotland, this 16th day of April, 1903.

JOHN MACDONALD.
THOMAS MACDONALD.
